US00D746363S

(12) **United States Design Patent**
Chen

(10) **Patent No.:** **US D746,363 S**
(45) **Date of Patent:** **** Dec. 29, 2015**

(54) **SPECTACLES FRAME**

- (71) Applicant: **Chun-Nan Chen**, Tainan (TW)
(72) Inventor: **Chun-Nan Chen**, Tainan (TW)
(**) Term: **14 Years**
(21) Appl. No.: **29/507,679**
(22) Filed: **Oct. 30, 2014**
(51) LOC (10) Cl. **16-06**
(52) U.S. Cl. **USPC D16/326; D16/311**
(58) **Field of Classification Search**

CLAIM

The ornamental design for a spectacles frame, as shown and described.

DESCRIPTIONFIG. 1 is a perspective view of a spectacles frame showing my design;
FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective schematic view illustrating an application of a spectacles frame showing my design. The broken lines shown in the figure are for illustrative purposes only and form no part of the claimed design.

1 Claim, 7 Drawing Sheets(56)
